W. G. LAIDLAW

BOTTLE CLOSURE

Filed April 25, 1927

Inventor.

Walter G. Laidlaw.

By Harry DeHaan.

Attorney.

UNITED STATES PATENT OFFICE.

WALTER G. LAIDLAW, OF SYRACUSE, NEW YORK, ASSIGNOR TO KLEEN KAP CORPORATION, OF SYRACUSE, NEW YORK, A CORPORATION OF NEW YORK.

BOTTLE CLOSURE.

Application filed April 25, 1927. Serial No. 188,379.

This invention relates to improvements in fibrous bottle closures of the type having a central disc-shaped body, that is disposed in the recess of the mouth of an ordinary 5 milk bottle, the said body being formed with an integral flexible flaring apron that overlies the annular bead of the mouth.

The object of the present invention is to provide means for stiffening the peripheral 10 margin of the apron of the closure for facilitating handling thereof, and at the same time rendering the said margin impervious to moisture, for preventing softening and distorting of the apron and rendering it 15 liable to separate from the bead and to allow germs and dirt to enter between the apron and the bead. A further object is to provide a lacquer-like coating, which may be applied by dipping the apron, the said 20 coating being of such nature that it dries or sets readily and quickly and becomes relatively hard, and yet is tough and slightly pliable, whereby when the coating is applied to the opposite faces of the apron, it stiffens 25 the periphery of the apron and renders the latter conformable to the flare of the bead when applied under pressure. The coating is also preferably slightly tenacious, for aiding in maintaining the contact of the closure 30 with the bead of the mouth, so that it requires considerable force to separate the apron from the bead for removing the closure. A further object is to provide the lacquer-like coating in different colors, 35 whereby the product of each milk producer or vendor in a community may be instantly recognized by the color of the coated closures; the said coating being of such nature that in case unauthorized persons attempt to 40 remove the closure (which may only be accomplished by lifting one side of the apron), the upward flexing of any portion of the coated margin after the disc is properly seated in the recess tends to fracture the 45 lacquer and renders the apron incapable of being restored to its original close contact with the bead of the mouth. This fracturing as well as the distortion of the apron will clearly indicate tampering.

50 The various features and parts of the invention will be understood from the detailed description which follows, and by reference to the accompanying drawing, in which—

Figure 1 is a central vertical section, showing 55 the neck and mouth of a common milk

bottle, to which my improvement is applied. Fig. 2 is a top plan view of the closure, showing the area coated with the lacquer. Fig. 3 is an edge view of the closure. And Fig. 4 is a bottom face view of the closure, showing 60 the coating applied to the underside of the apron.

In the drawing, 2 represents an ordinary milk bottle, having a neck 2' and a depressed mouth 3, which is surrounded by a 65 flaring bead 4. The bottom of the recess 3 comprises a ledge 5, which provides an annular seat for the bottle closure.

The present closure may follow any suitable construction but preferably consists of 70 a large disc of relatively thin pliant pulp-board, or the like, which is ordinarily molded by a machine for providing a central disc portion 6, the latter usually being overlaid with a reinforcing disc, as 7, of stiffer 75 cardboard, the disc portion 6 preferably being surrounded by a rolled flaring apron or flange 6', which is arranged to overlie the convex bead 4, when the discs are seated on the ledge 5.

The foregoing describes a well-known bottle closure, which is coming into common use. These closures effect the satisfactory sealing of the bottle mouth, but the flaring aprons, as 6', owing to the fact that they are 80 relatively thin, and in the process of rolling or molding the said aprons, the fiber becomes somewhat crushed and is rendered more or less limp, and tends to become ruffled and distorted in the vicinity of its peripheral margin and does not conform to or intimately 85 adhere to the curved surface of the bead. This invariably leaves a large number of 90 small openings or gaps between the apron and the bead to admit dirt and germs. It 95 is essential in a bottle closure of this type that the member 6—6' be relatively thin and light in order that it may be readily molded to the desired shape and in view of the fact that the normal stiffness of the material is 100 destroyed by the process of the manufacturing the closures, it is impossible to provide a convex apron that snugly fits the bead when the cap is applied to the bottle.

The present invention has for its primary object to provide simple and effective means for stiffening the peripheral margin of the apron 6' by coating, as at 8 and 8', the top and bottom surfaces thereof with 105 a quick-drying semi-liquid preparation, the 110

said coating being relatively thick and more or less elastic, and being preferably applied to the apron as it comes from the molding machine, and while the apron is still in its 5 normal concavo-convex state, the closures being handled thereafter in a manner to effect the rapid drying and setting of the coating without distorting the apron. By this method of treating the rolled apron 6', 10 the closure may be packed, shipped, and then applied by the usual capping machines in a manner to effect the close or intimate engagement of the apron with the bead 4, as shown in Fig. 1.

15 For this purpose, I prefer to employ a lacquer-like substance preferably prepared in a suitable viscous state, and which may be applied by dipping the peripheral margin of the closure in the semi-liquid, or by 20 any other well-known method. I prefer to coat the underside of the apron 6' that contacts with the bead 4, to a slightly greater extent than its external or top surface, as may be understood by comparing Figs. 2 25 and 4. By this means a broader surface of the lacquer is brought into contact with the glass, and as the said preparation when properly conditioned is preferably slightly tenacious, a broader and more effectual seal 30 of the parts results.

In practice the closures are stacked in a relatively tall cylindrical magazine, which is disposed adjacent the capping machine, and the closures are carried into the machine 35 by a shuttle-like member that travels back and forth beneath the magazine, and at each forward stroke moves the lowermost closure into the capping position. In performing its work, the feeding member 40 engages the peripheral margins of the closures with sufficient force to eject them from the magazine. The force required to eject the closures varies according to the height of the stack and weight exerted by the 45 stack upon the lowermost closure. It has been found that the feeding of the plain unlacquered paper closures is not reliable, for the reason that the aprons, as 6', having been rendered more or less limp by the 50 process of molding, as explained, tend to buckle and crush during the initial ejecting movement of said member and before the closure actually starts on its way toward the capping position. This distorting of the apron 55 results in the shortening of the effective stroke of the ejecting member to such extent that the mutilated closures are not carried forwardly the distance required to bring them in registry with the recess of the bottle 60 mouth. This not only interrupts and retards

the capping operation but also causes a waste and loss of a large number of closures. This trouble, annoyance and waste is entirely obviated by coating the aprons of the closure with the lacquer 8, which effect- 65

The coated apron 6' may be readily separated from the bead 4 by gripping it with 70 the finger nails, and by pulling on the loosened portion for peeling off the closure. The nature of the coating material is preferably such that in case of unauthorized removal of the cap, the lacquer will show 75 fracture where the apron is bent abruptly, by the separating operation, and will accordingly indicate visually the fact of such tampering. In case the closure is broken or distorted by the lifting or peeling of the 80 apron 6', the separated and mutilated portion of the apron cannot be again smoothed out and made to closely fit the bead without detection. The coating is furthermore preferably impervious to moisture, and prevents 85 the apron from becoming water-soaked and liable to become loose or fouled by dirt and germs.

By coating the closures with the lacquer 90 enables me to utilize somewhat lighter and cheaper grade of paper than heretofore employed for the purpose.

Having thus described my invention, what I claim, is—

A bottle closure including a disk like body 95 formed to seat in the recess of a bottle mouth and having a concavo-convex annular apron formed of material thinner than that of the disk and adapted to overlie the bead of the bottle mouth and being of a width so that its periphery terminates at substantially the center of the width of the bead, and a coating of quick drying and setting plastic composition covering the opposite faces of 100 the marginal portion of the apron, said composition being of such thickness and character so as to stiffen and maintain the predetermined shape of the marginal portion 105 of the apron, thereby to prevent buckling thereof, during the capping operation, said coating also covering the peripheral edge of the apron and being of a width to resist any tendency of the feeding shuttle 110 of the capping machine which engages said edge to distort the apron thereby to effect 115 accurate register of the apron with the bottle mouth.

In testimony whereof I affix my signature.

WALTER G. LAIDLAW.
